HERVEY G. CRAM, OF BUCKSPORT, MAINE, ASSIGNOR TO MAINE SEABOARD PAPER COMPANY, OF BUCKSPORT, MAINE, A CORPORATION OF MAINE

SEALPIT STOCK SAVER

Application filed September 24, 1931. Serial No. 564,812.

This invention relates to sealpits such as are used with mechanical filters, and the object of the invention is to provide a construction permitting the free utilization of the filtrate 5 as desired without waste and without adversely affecting the operation of the filter mechanism.

My invention finds a particular application in the paper making industry and for 10 convenience I shall specifically refer to such application in the following description from which, when taken in connection with the accompanying drawings, my invention may be well understood. In these drawings:—

Fig. 1 is a partial plan view of the sealpit; Fig. 2 is a section on the line 2—2 of Fig. 1 with parts broken away; and

Fig. 3 is a fragmentary section on the line 3—3 of Fig. 2.

Referring to Fig. 1 of the drawings, I have there shown a sealpit 5 which in this case is a concrete tank situated on the floor beneath mechanical filters. The filtrate or discharge through the wire mesh of the cylinder passes 25 downward to the sealpit through the barometric legs 7 and 9, the lower ends of which are submerged in the liquid retained in the sealpit, thus providing for a vacuum or suction in these legs. In the manufacture of paper 30 this filtrate has a very considerable value as a certain proportion of finer fibers will pass through the wire mesh with the filtrate into the sealpit. Therefore, in paper mill practice it is desirable to use as much of this 35 filtrate as possible for thinning stock, etc. It will be appreciated, however, that if an undue amount of the filtrate is drawn off at any given time the level in the sealpit may fall 40 below the bottoms of the legs 7 and 9 breaking the vacuum.

Heretofore it has therefore been customary to supply fresh water to the sealpit to maintain a predetermined level by establishing an 45 overflow over a suitable weir or dam. The excess water running over the dam, however, carried with it a considerable amount of the stock in the filtrate resulting in waste. The construction which I am about to describe obviates this difficulty.

I have herein shown as constructed adja-

cent to, herein, within the outlines of the tank 5, a chamber 11 to which make-up water is supplied by pipe 13, a constant level being maintained in the chamber 11 higher than the bottom of the legs 7 and 9, this herein being effected by providing an overflow at 55 dam 15, the overflow discharging through passage 17 to the sewer or to any convenient place of utilization. Provision is made whereby make-up water may flow from the 60 chamber 11 to the sealpit proper as the level of the filtrate in the latter falls to such an extent as to endanger the vacuum in the barometric legs while on the other hand flow from the sealpit to the chamber and hence its 65 waste over the dam is prevented. For this purpose the walls of the chamber 11 are provided with suitable openings 17 closed by the swinging gates 19 which open away from the chamber and toward the sealpit and which 70 constitute essentially check valves permitting flow from the chamber to the sealpit but preventing flow in the reverse direction. The bottoms of these gates, as seen by Fig. 2, are 75 beneath the level defined by the crest of the weir or dam 15.

It will thus be seen that if the level of the filtrate in the sealpit is high, water will flow into the chamber 11 and over dam 15, maintaining the level in the chamber. Then if 80 filtrate is drawn off from the sealpit and the level falls below that determined by the dam, the check valve gates 19 will open permitting water to flow into the sealpit to maintain the level and prevent breaking of the vacuum 85 in the legs. If the level of the filtrate in the sealpit becomes higher than the level of the fresh water inside the chamber 11, the gates automatically close by gravity and stock can 90 not flow through these gates into the chamber and hence over the dam to the sewer to be wasted.

I am aware that the invention may be embodied in other specific forms without departing from the spirit or essential attributes thereof, and I therefore desire the present embodiment to be considered in all respects as illustrative and not restrictive; reference 95 being had to the appended claims rather than 100

to the foregoing description to indicate the scope of the invention.

Claims:

1. In combination with the sealpit and barometric leg discharging thereto, a chamber adjacent to the sealpit having means for maintaining a level of water therein above the bottom of said leg and check-valve means between the chamber and pit opening toward the latter.
2. In combination with a sealpit, a barometric leg through which fluid is supplied thereto, means to supply make-up fluid and means effective only when the fluid in the sealpit falls below a determined level to admit fluid from said supply to the pit.
3. In combination with a sealpit, a barometric leg through which fluid is supplied thereto, a tank having an overflow at a level above the bottom of said leg, means to supply make-up fluid to said tank and a one-way connection between the tank and pit through which fluid may flow from the former to the latter when the fluid in the latter falls below a determined level.

In testimony whereof, I have signed my name to this specification.

HERVEY G. CRAM.
